(57) **CLAIM**

The ornamental design for a bicycle light, as shown and described.

DESCRIPTION

FIG. 1 is a perspective view of a bicycle light;
FIG. 2 is an exploded perspective view thereof;
FIG. 3 is a side elevation view thereof;
FIG. 4 is an exploded side elevation view thereof;
FIG. 5 is a front elevation view thereof;
FIG. 6 is a rear exploded perspective view thereof;
FIG. 7 is a rear elevation view thereof;
FIG. 8 is a perspective view thereof, but showing the bicycle light in use mounted on a bicycle handle shown in broken lines; and,
FIG. 9 is a side view thereof.

The broken lines shown in the drawings represent environment that form no part of the claimed design.

1 Claim, 9 Drawing Sheets
